H. J. Denman,
Atty.

UNITED STATES PATENT OFFICE.

THOMAS HENRY MARTEN, OF NEW YORK, N. Y.

SHIP'S DAVIT.

1,313,404.

Specification of Letters Patent.

Patented Aug. 19, 1919.

Application filed April 6, 1917; Serial No. 160,215. Renewed January 13, 1919; Serial No. 270,945.

To all whom it may concern:

Be it known that I, THOMAS HENRY MARTEN, a subject of the King of Great Britain, and resident of the city and State of New York, in the United States of America, have invented certain new and useful Improvements in Ships' Davits, described in the following specification and illustrated in the accompanying drawings, that form part 10 of the same.

The principal objects of the invention are to devise a form of davit for handling ships' boats which may be operated with ease and the minimum of mechanism to 15 carry the boat outboard the maximum distance without danger of fouling the rail of the ship.

A further object is to improve that form 20 of davit in which the boom swings in a vertical plane so as to minimize the stress upon the means for swinging the boom and to reduce the labor of operating the boom.

A still further object is to devise a structure which will be extremely rigid and 25 which may be manufactured at very low cost and which is adapted to utilize the advantageous features of the rotating type of boom with the desirable features of the vertically swinging boom and further to 30 overcome the difficulties met with in clearing the boat from the chocks.

Many different forms of mechanically operated davits have been devised some of 35 which swing the boom in a vertical plane and others rotate the boom upon its longitudinal axis to swing the boat supporting end in a horizontal plane. The principal difficulty of the vertical swinging boom is that in obtaining the desired outreach the 40 boom head and consequently the boat drops considerably in the latter phases of its outward travel and the frame and operating mechanism required is cumbersome and expensive and in the rotating type the disadvantage is that the boom operates in a 45 transverse plane and has no upward movement to effect the lifting of the boat from its rests.

The present invention consists essentially 50 in effecting a combined vertical swinging and axially rotating movement of the boom.

In the accompanying drawings Figure 1, is a side elevational view of a davit constructed in accordance with this invention showing the davit boom in the inboard position in full lines and in the extreme outboard position in dotted lines.

Fig. 2 is an end elevational view of the davit shown partly in section.

Fig. 3 is a detail horizontal section 60 through the line *a*—*b* of Fig. 1.

Fig. 4 is a side elevational view of a modified form of davit and Fig. 5 is an end elevational view.

Referring to the drawings, the frame 1 is 65 a rigid cast structure of rectangular form having the cross web 2 extending between the end standards 3 and 4 intermediate of their height, said standards having horizontal journals 5 and 6 adjacent to the top 70 in which the screw spindle 7 is journaled.

A bar 8 is rigidly secured between the upper ends of the standards in parallel arrangement with the spindle 7 and forms a 75 guide for the crosshead 9 which is in the form of a sleeve encircling said bar. The crosshead 9 is formed with a downwardly extending lug 11 which is threaded upon the spindle 7 so that upon the rotation of the spindle the crosshead will be caused to 80 travel on the guide.

A pivot pin 12, rigid with the crosshead 9, extends laterally from one side thereof and pivotally supports a sleeve 13 which is provided with a projecting lug 14 through 85 which said pin extends.

The davit boom 15 is slidably and rotatably held intermediate of its length in the sleeve 13 and the lower end 16 is rotatably stepped in a cup 17 pivotally mounted at 90 the base of the frame and adapted to swing in a vertical plane.

The cross web 2 of the frame is formed with a quadrantal toothed rack 18 on the side adjacent to the boom, said rack being 95 concentric to the pivotal center of the cup 17.

A sleeve 19, keyed or otherwise rigidly secured upon the boom 15 below the sleeve 13 is formed with a toothed segment 20 100 which meshes with the teeth of the rack 18 so that as the boom swings in a vertical

plane it will be caused to rotate on its longitudinal axis. A web 21 is preferably cast integral with the rack teeth 18 at the upper side to strengthen and protect the teeth 5 from injury.

The boom 15 is formed with a curved upper end 22 and is of the axially rotating type having a suitable eye 23 at the upper end to receive the shackle of the upper 10 block of the boat falls.

The boom is preferably set so that in the extreme inboard position the post slopes inboard in a vertical plane and the curved upper end is turned laterally over the boat 15 and preferably pointing inboard. Upon the rotation of the spindle 7 by means of the crank 24 the crosshead 9 is moved outwardly and swings the boom in a vertical plane. Coincident with the outboard swing of the 20 boom post in a vertical plane the said post is rotated axially through the engagement of the toothed segment of the sleeve 19 with the rack 18 thereby swinging the curved upper end of the boom in an outboard direction. 25

The pivot support of the lower end of the boom is preferably arranged about midway of the inboard and outboard positions of angularity of the boom.

In the operation of this davit, the vertical swinging movement from an inboard inclination and the first part of the transverse swing of the outer end of the boom causes the said outer end of the boom to travel in 35 an upward and outward curve thereby taking up any slack in the falls and lifting the boat clear of the chocks. The continued double swinging movement carries the boat outboard in a path closely approximating the horizontal being first raised slightly then 40 toward the outer position lowered slightly, the path being slightly curved and the highest point in the movement being when the boat is clearing the rail of the ship.

The movement is very positive and extremely simple and owing to the rotative movement the vertical swing required to obtain the maximum reach is very short. Consequently the screw spindle is short and 50 a slow pitch thread may be used. This enables the operation to be effected with the minimum application of power upon the operating crank.

The short throw of the boom post allows 55 of an extremely narrow frame, therefore the device may be readily placed so as not to interfere with deck space and being small and compact the weight and consequently the cost is reduced to the minimum.

In the form of davit shown in Figs. 1, 2 60 and 3 the rotating movement is shown as being effected by meshing gear teeth but other means of effecting both the axial and vertical swinging movements may be adopted 65 without departing from the spirit of the

invention which is to effect this axial rotation coincident with the vertical pivotal movement.

A modified form of the device is shown in Figs. 4 and 5 in which the post of the curved 70 boom 15 is rotatably mounted upon a bracket 25 pivotally secured to the ship's deck so as to swing in a vertical plane. The bracket 25 is supported and operated in its swinging movement to move the boom in a vertical plane by an adjustable strut 26 pivotally connected at one end to the said bracket 25 and at the other end to a rigid bracket 27. 75

The coincident axial rotation of the boom 80 is effected by means of an arm 28 rigidly secured to the boom post and a link 29 is pivotally connected at one end to the outer end of said arm and at the other end to the rigid bracket 27. As the boom swings outwardly in the vertical plane the link 29 pulls upon the arm 28 and rotates the boom post. 85

What I claim as my invention is:

1. A boat davit comprising a rigid frame secured to the deck, a boom pivotally and 90 rotatably mounted in the base of said frame and adapted to swing in a vertical plane from an inwardly inclined to an outwardly inclined position and to rotate axially, and means for effecting an axial rotation of the 95 boom coincident with the swinging movement.

2. A boat davit comprising a rigid frame secured to the deck, a boom pivotally and 100 rotatably mounted in the base of said frame and adapted to swing in a vertical plane and to rotate axially, means slidably supported on said frame engaging said boom intermediate of its length and supporting it against fore and aft stresses, means for operating said slideable member in said frame, and means for effecting an axial rotation of the 105 boom coincident with the swinging movement.

3. A boat davit comprising a rigid frame 110 secured to the deck, a boom pivotally and rotatably mounted in the base of said frame and adapted to swing in a vertical plane and to rotate axially, a crosshead slidably arranged on said frame, a sleeve pivotally connected to said crosshead and slidably encircling the boom, a screw spindle journaled in the frame and operating said crosshead, and means for effecting an axial rotation of the 115 boom coincident with the swinging movement. 120

4. A boat davit comprising a rigid frame secured to the deck, a boom pivotally and 125 rotatably mounted in the base of said frame and adapted to swing in a vertical plane and to rotate axially, means slidably supported on said frame engaging said boom intermediate of its length and supporting it against fore and aft stresses, means for operating said slideable member in said frame, 130

a toothed rack arranged on the side of said frame, and a toothed gear secured to said boom and meshing with said rack.

5. In a boat davit, in combination a rigid unitary cast metal frame having a segmental gear rack arranged on one side intermediate of its height, a bar crosshead guide secured in the top of said frame, a crosshead slidably arranged on said bar, a screw spindle

arranged below said guide and operating 10 said crosshead, a socket member pivotally supported in the base of the frame, a boom stepped in said socket member, a sleeve rotatably and slidably encircling said boom and pivotally connected to said crosshead, and a 15 toothed gear secured to said boom and meshing with said segmental rack.

THOMAS HENRY MARTEN.
